(57) **CLAIM**

We claim the ornamental design for a toothbrush handle, as shown and described.

DESCRIPTION

FIG. 1 is a left, bottom, front perspective view of a toothbrush handle showing our new design;

FIG. 2 is a left side elevational view thereof; and,

FIG. 3 is a front elevational view thereof.

The broken lines showing the rest of the handle and a brush head are included for the purpose of illustrating portions and environmental structure of the toothbrush handle that form no part of the claimed design.
